Primary Examiner — Daniel J Domino*Assistant Examiner* — Lee D. Starr(74) *Attorney, Agent, or Firm* — Jose Cherson Weissbrot(57) **CLAIM**

The ornamental design for an Adapter, as shown and described.

DESCRIPTION

FIG. 1 is a front elevational view of an Adapter showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and

FIG. 7 is a perspective view thereof.

The broken lines in the drawings depict portions of the Adapter that form no part of the claimed design.
